MANUALLY OPERABLE SELECTOR

Edward Shipton, London, England

Application June 19, 1935, Serial No. 27,429
In Great Britain June 21, 1934

19 Claims. (Cl. 179—90)

The present invention relates to manually operable selectors suitable for use in intercommunicating telephone systems and the like. The object of the invention is to provide a selector mechanism which is simple and reliable in operation and which is cheap to produce.

A further object of the invention is to construct a selector switch substantially completely from standard automatic telephone parts. Another object is to provide a switch which may be used for calling more than ten lines whilst still using a standard finger hold plate and without the necessity of installing a complete automatic telephone system.

According to the present invention the selector comprises two or more groups of contacts with which is or are adapted to operate one, two or more wipers, a discriminating mechanism being operated to cause the wiper or wipers to be selectively connected, either mechanically or electrically, to a contact in the first, second or subsequent contact group. The discriminating mechanism is preferably operated in accordance with the first, second or subsequent times that the finger hold plate is pulled round.

In the preferred form of the invention only a single wiper is used which when the finger hold plate is pulled round for the first time engages with a contact of the first contact group and, when the finger hold plate is pulled round for the second time with a contact of the second contact group. The two contact groups may be arranged on the same circle, the contacts of one being interposed between the contacts of the other, and the selecting of which contact group the wiper cooperates with depends upon whether the finger hold plate is pulled round for the first, second or subsequent times, each pull changing the ratio of wiper travel to finger hold plate movement. This may be effected by causing the mechanism of the switch to shift the wiper forward when the finger hold plate is pulled round for the second time a distance equal to half the distance between two contacts of the same group or if the finger hold plate is meant to be pulled round for the third time to a third the distance between two adjacent contacts of the same group and so on.

The wiper may be pushed round by a member which when the dial is pulled for the first time moves the wiper by one portion thereof and is so arranged that when the dial moves back the member moves transversely so that a second portion thereof, which is a distance in advance of the first mentioned portion corresponding to one half the distance between two contacts of the

same group, engages with the wiper when the dial is pulled round for a second time, whereby during the second pull the wiper will be moved to a contact of the second group and held thereon.

The wiper may be held in position by a pawl 5 and ratchet mechanism, a spring being provided for restoring the wiper to normal when released.

In order that the invention may be more clearly understood reference will now be made to the accompanying drawings which show various embodiments thereof applied to an intercommunicating telephone system for twenty subscribers.

In the drawings:—

Fig. 1 represents a side view, partly in section, of a desk telephone set embodying the selector 15 switch according to the invention.

Fig. 2 is a back view of the selector switch illustrated in Fig. 1 but on a larger scale.

Fig. 3 shows a view looking along the line A—A in Fig. 1 in the direction of the arrows but on a larger scale.

Fig. 4 shows a detail of the discriminating mechanism looking along the line B—B in Fig. 3.

Fig. 5 shows a circuit arrangement for an intercommunicating telephone system according to the invention.

Fig. 6 shows diagrammatically a modified arrangement of the invention.

Referring to Fig. 1 of the drawings, 1 represents the casing of the desk set, in an aperture in the front of which is mounted the number plate 2 in which the finger hold plate 3 is journaled, the spindle of the finger hold plate passing through the number plate carrying at its inner end a driving disc 4 (see also Figs. 3 and 4) secured thereto by a nut 5. The spindle is secured to one end of a spiral return spring arranged in the casing 6 in known manner in order to restore the finger hold plate to the normal position where it engages with a stop.

To the inner side of the aperture behind the number plate 2 is mounted the contact carrying ring 7 constructed of insulating material and attached to the casing 1 by screws (not shown). In this contact carrying ring are embedded the twenty-one contacts 8. Also carried by this contact carrying ring is the bearing 9 for the spindle 10 arranged coaxial with the finger hold plate spindle. At one side the spindle is formed with an enlarged collar 11 and a flat end disc 12 to which is attached a driving member 13 shaped as shown, the upwardly extending portion 13a thereof being adapted to be engaged or collected as hereinafter described by the discriminating member 14 (Figs. 3 and 4), carried by the driv-

ing disc 4, when the finger hold plate is rotated, thus to rotate the spindle 10. Also mounted on the disc 12 is the wiper 15 adapted to wipe over the contacts 8. A spiral spring for restoring the wiper to normal where it engages with a fixed stop is located in the casing 16 and arranged in well-known manner. Attached to the spindle 10 at the rear side of the spring casing is the ratchet 17 which is held in position by a nut 19 which also serves to hold the collar 11 up against the bearing 9. The ratchet 17 is shown as comprising two ratchet wheels having ten teeth each and displaced so that the teeth of one wheel are arranged intermediate the teeth of the other wheel. Alternatively, a single ratchet wheel having twenty teeth may be used.

The construction above described has the advantage that the contact ring carrying the wiper is quite separate from the number plate and finger hold plate, so that either of these members may be removed from the casing by undoing securing screws without interfering with the other member. Driving connection between the two spindles is made by the member 14 collecting the driving member 13 when the finger hold plate is rotated.

Pivoted at 20 (see Fig. 2) to the contact carrying ring 7 is the pawl 21 having an upwardly bent portion 22 which is adjacent the teeth of the ratchet 17, a leaf spring 23 being provided and arranged to force the pawl in engagement with the ratchet. Also extending from the other arm of the pawl is an upwardly inclined projection 24 shaped as shown which is adapted to engage with the projecting portion 25 of the lever 26 pivoted to a bracket on the contact carrying ring at 28 and operated by the lower end of the spindle operated by the telephone cradle 29. When the cradle is depressed the projecting portion 25 of the lever 26 engages with the inclined portion 24 of the pawl to cause the pawl to rotate in a clockwise direction (Fig. 2) to move the upwardly bent portion 22 out of the path of the teeth of the ratchet. When the telephone is lifted from the cradle, however, the cradle is raised and thus allows the pawl to move into the path of the teeth of the ratchet under the action of the spring 23.

In order to absorb the shock when the wiper 50 is restored to normal after being released from a contact, a horse-shoe shaped spring 50 (Figs. 2 and 3) is provided which is looped about the collar 11. One end of the spring engages in the hole 51 and the other end in the hole 52 which is larger than the diameter of the wire of the spring. As will be readily understood from Fig. 3, the downwardly extending portion 13b of the driving member 13 hits against the spring 50 when it springs back to normal, the spring 50 moving in the hole 52 to absorb the shock.

The movement of the wiper by the finger hold plate is effected by the discriminating member 14 carried by the driving disc 4 which engages with the upturned end 13a of the driving member 13 attached to the wiper shaft. The member 14 is pivoted at 14a to the driving disc and its leading edge is formed with a stepped portion 14b, the depth of the step being equivalent to the distance which this member has to move in order to move the wiper from one contact to the next. A light spring 14c is provided tending to force the pivoted member 14 outwards.

When the dial is pulled round for the first time the driving member 13 is moved forward by the step of the pivoted member engaging with

the upturned portion 13a and is prevented from moving outwards by the side of the step engaging with this upturned portion. When, however, the finger hold plate is released the wiper is held in position whilst the finger hold plate moves back to normal. The light spring 14c then causes the stepped discriminating member to move outwards until the pin 14d engages the end of the aperture 4a in the driving disc. On pulling the dial round for the second time it is the advanced leading edge of the member 14 which pushes forward the upturned portion 13a of the wiper driving member. It will be understood, therefore, that when the dial is pulled round to the finger stop for the first time the wiper will stop on one or other of the first, third, fifth, etc., contacts, and when it is pulled round to the finger stop for the second time the wiper will stop on either one or other of the second, fourth, sixth, etc., contacts.

When the finger hold plate returns to normal the pin **14d** engages with a guide which, in the example shown, is the end of a contact spring **31** of the switch **30**, the purpose of which will be hereinafter described, which pushes the stepped member inwards against the action of the spring **14c** so that when the wiper is restored to normal the upturned portion **13a** thereof can engage over the step so as to be moved forward by the step **14b** when the dial is next pulled round. 30

In order to prevent clicks from being heard at any station which is already speaking when the wiper of another calling station passes over the corresponding contact, a switch member 30 carried from the underside of the number plate 2 is provided, the contacts 31, 32 of which are closed by the pin 14d carried by the member 14 only when the driving disc 4 is in its normal position (see Fig. 3). As soon as the finger hold plate is moved, the contacts spring open to disconnect the battery supply from the wiper so that during the actual selecting operation no circuits are completed. After the selection is made, however, and the finger hold plate released, it returns to normal to close the contacts and thus connect the battery supply to the wiper and complete the speech circuit.

In order to effect the ringing when the called station is selected the button 33 is depressed to cause the metallic leaf spring 34 to engage with the metallic member 35 and complete the circuit. 50

Arranged within the telephone casing 1 are also the telephone cradle switch mechanism 36, the calling buzzer 37 and the retard 38 together with any other mechanism necessary at the station. The bottom 39 of the casing 1 may be removed to inspect the mechanism. 55

The operation of the mechanism is as follows:—The telephone receiver is first raised and if the number to be called is in the first ten numbers, the finger hold plate is merely pulled round to the desired number whereupon the stepped portion 14b of the member 14 engages with or collects the member 13 to rotate the wiper to the contact corresponding to the selected station. 60 If the number to be called is from 11 to 20, the finger hold plate is first pulled round to number "1", and released, and then to the second digit of the number to be called. When the finger hold plate returns to normal after it is pulled round for the first time whilst the wiper remains on the first contact as hereinafter explained, the stepped portion of the member 14 is released from the upturned portion 13a of the driving member 13 so that when it is pulled round for 65 70 75

the second time the leading edge of this member moves the wiper on to and stops it on one of the second group of contacts, that is either the second, fourth, sixth, etc., in the circle.

5 On releasing the finger hold plate it is returned to normal under the action of its associated spring but the wiper is held in position on the called contact by the upwardly bent portion 22 of the pawl 21 engaging with one of the teeth 10 of the ratchet 17. When the call is finished, however, and the telephone replaced, the telephone cradle is depressed thus moving the pawl out of the path of the ratchet and allowing the wiper to return to normal under the action of 15 its associated spring.

It will be understood that when a station from number 11 to 20 is called, the finger hold plate may be pulled round to any number on the first pull provided that it is not greater than the 20 second digit of the number. The first pulling operation merely allows the discriminating member to operate so that on the second pull a different ratio of wiper travel to finger hold plate movement is obtained.

25 Fig. 5 shows a circuit diagram of the instrument according to the invention and will now be described to explain the method of operation of the circuit. In this figure the twenty-one contacts of the selecting mechanism are shown, the 30 first or home contact being marked H and the remaining contacts of the two contact groups 1 to 10 and 11 to 20 respectively. In station 1 the contact H and 1 may be strapped together, in station 2 the contacts H and 2, and so on 35 for the other stations, but this strapping of two contacts is not necessary for satisfactory operation. Normally the wiper 15 is at rest on the home contact and the contacts 31, 32 of the switch 30 are closed. When the telephone is on the 40 cradle the contacts 40 of the cradle switch are closed and the contacts 41 and 42 are opened. On a call arriving at the station the negative pole of the battery is connected through the contact H, wiper 15, conductor 43, switch contacts 31, 32, contacts 40, buzzer 37, conductor 44 to the positive pole of the battery thus causing 45 the buzzer to operate to indicate that a call is waiting to be answered. On lifting the telephone the contacts 40 are opened to open the buzzer circuit and the contacts 41 and 42 are closed. Through the closure of contacts 41, the speech 50 circuit is completed through the conductor 45, telephone instrument 46 and conductor 47 to the positive pole of the battery. The talking current at the station is provided through the 55 circuit, negative pole of battery, conductor 48, retard 38, contacts 42, conductor 45, telephone instrument 46 to the positive pole of the battery. The calling and called stations can then talk 60 and on completing the conversation the telephone is replaced thus opening the contacts 41, 42 and closing the contact 40 to complete the buzzer circuit in readiness for another call.

Should it be desired to make a call, the subscriber removes the telephone and pulls around 65 the finger hold plate either once or twice and thus moves the wiper 15 to the desired contact, say No. 4. Immediately the finger hold plate has been moved from normal the contacts 31, 32 of the switch 30 are opened thus disconnecting 70 the wiper 15 from the battery and preventing clicks occurring in the receivers of any station, over which the wiper 15 passes, which may be operating at the time. When the finger hold plate is released the wiper remains on contact

No. 4 but the finger hold plate is restored to normal there to close the contacts 31, 32. The operator then presses the ringing button 33 to cause the contacts 34, 35 to send the ringing current from the negative pole of battery through conductor 49, contacts 35, 34, conductor 43, wiper 15, contact No. 4 to the home line at station No. 4 and through its corresponding buzzer circuit to the positive pole of battery as explained above when the station illustrated was considered as 10 being the called station. When the telephone instrument at the called station is lifted, the speech circuit is completed from positive pole of battery, conductor 47, telephone instrument 46, conductor 45, contact 41, contacts 32, 31, conductor 43, wiper 15, contact No. 4, home contact of station No. 4 and through its corresponding wiper 15, conductor 43 etc., to the negative pole of the battery as described above. The energizing current for the local talking circuit is provided through the retard 38 at each station as 20 has already been described. On completing the call, the telephone instrument is replaced on the cradle thus releasing the pawl to allow the wiper 15 to return to normal and thus to restore the 25 whole circuit to be ready to receive or make a new call.

Fig. 6 shows diagrammatically a modified arrangement according to the invention in which the wiper shaft carries two or more wipers, in the example shown two wipers 60, 61, which co-operate with separate groups of contacts 62, 63. According as the finger hold plate is pulled around for the first, second, or subsequent times, the wipers are selectively connected in circuit 30 in sequence whereby the circuit is completed through the first, second or subsequent contact group. This is effected by means of a discriminating switch which automatically switches over 35 from one of the wipers or contact groups to the next in accordance with the number of times the finger hold plate is moved. The discriminating mechanism shown comprises a wiper arm 64 adapted to wipe over contacts 65, 66 connected to the wipers 60, 61 respectively. The wiper arm 40 45 64 is mounted on a spindle carrying an advancing disc 67 which is stepped forward by a ratchet mechanism 68 each time the finger hold plate, which is mounted on the spindle 69, is moved. On rotating the finger hold plate the cam 70 50 carried by the finger hold plate spindle moves the ratchet mechanism forward in steps where it is retained by the catch 71. If the finger hold plate is only pulled round once the wiper 64 stops on the contact 65 and thus completes the 55 circuit from the wire 43, which corresponds to the same wire in Fig. 5, through the wiper 60. If the finger hold plate is pulled round for a second time the wiper 64 is stopped on the contact 66 to complete the circuit through the wiper 61. 60 When the telephone is replaced on the cradle the catch 71 is released to allow the advancing disc 67 and wiper 64 to return to normal position under the action of a spring (not shown).

Instead of operating the discriminating arm 65 by the forward movement of the finger hold plate it may alternatively be operated by the restoration of the finger hold plate to normal, i. e. the power of the spring for returning the finger hold plate to normal is also used for operating the 70 discriminating mechanism.

The wipers 60, 61 may be mounted on a common wiper spindle but insulated from one another. The wipers may engage with separate contact banks by making one wiper longer than 75

the other so that the wipers wipe over two concentric circular banks of contacts. Alternatively, the wipers may be of the same length and engage between groups of contacts arranged 5 above and below the wipers or, again, the wipers may extend in opposite directions from the wiper shaft and engage with separate groups of contacts arranged on opposite parts of the same circle. In another construction the wipers may 10 be of the same length and be arranged close together side by side, the contacts of one group being interposed between the contacts of the next. Connection with the wipers may be made by pig-tails, slip rings, or in any other suitable 15 manner.

If desired, the advancing mechanism 65 may be arranged to be operated manually so that the selection of which wiper is made effective is controlled at the will of the operator in accordance 20 with the setting of the manual switch.

In a further modification the selection of the station to be called may be effected by employing two or more ringing buttons, each being connected through a different wiper or contact 25 group of the selector so that although the wiper connects with two or more stations, or all the wipers connect with a station, only that station is called which is in the group corresponding to the ringing button which is operated.

30 It will be understood that various other modifications may be made without departing from the scope of the invention as defined by the appended claims. For example, instead of shifting the wiper in the arrangement shown in Fig. 1 35 when the finger hold plate is pulled round for the second or subsequent time, this operation may cause the contact bank itself to be displaced to cause the wiper to engage with the contact of another group. Further, throughout this specification reference has been made to using a finger hold plate for operating the selector mechanism, but, of course, any other convenient form of 40 manually operable device may be used for operating the selector.

45 Moreover, the switch according to the invention is not limited in its application to intercommunicating telephone systems but can be used in intercommunicating signalling systems of any kind, in remote control systems, and in other like 50 systems where it is desired to select and make contact with one of a plurality of remote stations.

I claim:—

1. A manually operable selector comprising at 55 least two groups of contacts, a wiper cooperating with each of said contact groups, a manually operable member to move said wiper on to a contact, and discriminating means for selecting the contact group over which a signal is transmitted.

60 2. A manually operable selector comprising at least two groups of contacts, a separate wiper cooperating with each of said contact groups, a manually operable member to move said wipers on to corresponding contacts in their respective 65 groups, and discriminating means for selecting the wiper through which the circuit is to be completed.

3. A manually operable selector comprising at 70 least two groups of contacts, a separate wiper cooperating with each of said contact groups, a manually operable member to move said wipers on to corresponding contacts in their respective groups, and switching means for connecting one of the wipers in circuit.

75 4. A manually operable selector comprising at

least two groups of contacts, a wiper cooperating with each of said contact groups, a manually operable member to move said wiper, the forward movement of which determines the contact on to which the wiper is moved, means other than the manually operable member for holding the wiper in the position to which it is moved, means for restoring the manually operable member to normal when released, and discriminating means operated by the movement of the manually operable member to select the contact group with which the wiper cooperates to complete the circuit. 5

5. A manually operable selector comprising at 15 least two groups of contacts, a separate wiper cooperating with each of said contact groups, a manually operable member to move said wipers on to corresponding contacts in their respective groups, the forward movement of said member determining the contacts on to which the wipers are moved, means other than the manually operable member for holding the wipers in the position to which they are moved, means for restoring the manually operable member to normal when released, and discriminating means operated by 20 the movement of the manually operable member to select the wiper through which the circuit is to be completed. 25

6. A manually operable selector comprising at 30 least two groups of contacts, a separate wiper cooperating with each of said contact groups, a manually operable member to move said wipers on to corresponding contacts in their respective groups, the forward movement of said member determining the contacts on to which the wipers are moved, means other than the manually operable member for holding the wipers in the position to which they are moved, means for restoring the manually operable member to normal when released, and switching means operated by 35 the movement of the manually operable member for connecting one of the wipers in circuit, the setting of the switching means being determined by the number of times the manually operable member is moved. 40

7. A manually operable selector comprising at 45 least two groups of contacts, at least one wiper cooperating with said contacts and mounted on a wiper carrier, a finger hold plate to move said wiper carrier, means for holding the wiper carrier in the position to which it is moved, means for restoring the finger hold plate to normal when released, and discriminating means which is operated selectively to complete an electric circuit through one of the contact groups in accordance 50 with the number of times the finger hold plate is operated. 55

8. A manually operable selector comprising at 60 least two groups of contacts, a wiper cooperating with said contacts, a finger hold plate to move said wiper, means for holding the wiper on the contact to which it is moved, means for restoring the finger hold plate to normal when released, and a discriminating mechanism which is operated to cause the wiper to move mechanically to stop on a contact in one of the contact groups in accordance with the number of times the finger hold plate is operated. 65

9. A manually operable selector comprising a 70 rotatable finger hold plate, a rotatable wiper, a plurality of contacts arranged in a circular contact bank over which said wiper is adapted to be moved, means for holding said wiper on the contact to which it is moved, means interconnecting said finger hold plate and wiper whereby the wip- 75

er is moved forward on the forward movement of the finger hold plate but such that when released the finger hold plate can return to normal without the wiper, and means for changing the 5 ratio of wiper travel to finger hold plate movement in accordance with the number of times the finger hold plate is operated.

10. A manually operable selector comprising a rotatable finger hold plate, a rotatable wiper, a 10 plurality of contacts arranged in a circular contact bank over which said wiper is adapted to be moved, means for holding said wiper on the contact to which it is moved, means interconnecting said finger hold plate and wiper whereby the 15 wiper is moved forward on the forward movement of the finger hold plate but such that when released the finger hold plate can return to normal without the wiper, means for changing the ratio of wiper travel to finger hold plate movement in accordance with the number of times the finger hold plate is operated, and switch contacts 20 operated by said finger hold plate when in its normal position.

11. A manually operable selector comprising a 25 rotatable finger hold plate, a rotatable wiper, a plurality of contacts arranged in a circular contact bank over which said wiper is adapted to be moved, means for holding said wiper on the contact to which it is moved, means interconnecting 30 said finger hold plate and wiper whereby the wiper is moved forward on the forward movement of the finger hold plate but such that when released the finger hold plate can return to normal without the wiper, means for changing the 35 ratio of wiper travel to finger hold plate movement in accordance with the number of times the finger hold plate is operated, means under the control of the switch hook for releasing the wiper, and means for restoring the wiper to normal 40 when released.

12. A telephone set for use in intercommunicating telephone systems comprising a telephone instrument, a switch hook for supporting said instrument, a rotatable finger hold plate, a rotatable 45 wiper mounted coaxial with said finger hold plate, groups of contacts associated with said wiper, a pawl and ratchet mechanism for holding said wiper in position on any contact to which it is moved, means for releasing said pawl when 50 the switch hook is depressed, a spring for restoring said wiper to normal when released, a discriminating member moved with the finger hold plate for pushing the wiper forwards, a spring for restoring said finger hold plate to normal 55 when released, and means for shifting said discriminating member so that the ratio of wiper travel to finger hold plate movement is changed when the finger hold plate is pulled round for a second time.

60. 13. A manually operable selector comprising a rotatable finger hold plate, a rotatable wiper, a plurality of contacts arranged in a circular contact bank over which said wiper is adapted to be moved, means for holding said wiper on the contact to which it is moved, means interconnecting 65 said finger hold plate and wiper whereby the wiper is moved forward on the forward movement of the finger hold plate but such that when released the finger hold plate can return to normal without the wiper, means for restoring the finger hold plate to normal when released, a stepped member moved with the finger hold plate for pushing the wiper forwards, and means for moving the stepped member transversely when 70 the finger hold plate moves back after it has been 75

pulled forwards whereby the wiper is moved forwards by an advanced portion of the member when the finger hold plate is pulled forwards a second time.

14. A manually operable selector comprising a 5 rotatable finger hold plate, a rotatable wiper, a plurality of contacts over which said wiper is adapted to be moved, means for holding the wiper on the contact to which it is moved, a stepped member moved with the finger hold plate for 10 pushing the wiper forwards, means for restoring the finger hold plate to normal when released, a step formed on said stepped member, a spring tending to move the stepped member transversely, a driving member attached to the wiper which is 15 pushed forwards by the stepped member and in the normal position engages over the step to prevent the spring from moving the stepped member transversely, and means for moving the stepped member against the action of the spring 20 when the finger hold plate is in its normal position.

15. A manually operable selector comprising a 25 rotatable finger hold plate, a rotatable wiper, a plurality of contacts over which said wiper is adapted to be moved, means for holding the wiper on the contact to which it is moved, a stepped member moved with the finger hold plate for 30 pushing the wiper forwards, means for restoring the finger hold plate to normal when released, a step formed on said stepped member, a spring tending to move the stepped member transversely, a driving member attached to the wiper which is 35 pushed forwards by the stepped member and in the normal position engages over the step to prevent the spring from moving the stepped member transversely, and switch contacts which are closed by said stepped member when the finger hold plate is in its normal position, said switch contacts moving the stepped member against the 40 action of the spring.

16. A manually operable selector comprising a rotatable finger hold plate, a rotatable wiper, a plurality of contacts arranged in a circular contact bank over which said wiper is adapted to be moved, means for holding said wiper on the contact to which it is moved, means interconnecting said finger hold plate and wiper whereby the wiper is moved forward on the forward movement of the finger hold plate but such that when released the finger hold plate can return to normal without the wiper, means for changing the ratio of wiper travel to finger hold plate movement in accordance with the number of times the finger hold plate is operated, means for releasing the wiper, means for restoring the wiper to normal when released, and a spring for absorbing the shock when the wiper is restored to normal. 50 55

17. A manually operable selector comprising a 60 rotatable finger hold plate, a rotatable wiper, a plurality of contacts arranged in a circular contact bank over which said wiper is adapted to be moved, a ratchet wheel and pawl for holding said wiper on the contact to which it is moved, means 65 interconnecting said finger hold plate and wiper whereby the wiper is moved forward on the forward movement of the finger hold plate, a spring for restoring the finger hold plate to normal when released, means for changing the ratio of wiper travel to finger hold plate movement in accordance with the number of times the finger hold plate is operated, means for releasing the pawl, and a spring for restoring the wiper to normal 70 when the pawl is released. 75

18. A telephone set for use in intercommunicating telephone systems comprising a telephone instrument, a switch hook for supporting said instrument, a rotatable finger hold plate, a rotatable wiper mounted coaxial with said finger hold plate, groups of contacts associated with said wiper, a pawl and ratchet mechanism for holding said wiper in position on any contact to which it is moved, means for releasing said pawl when the switch hook is depressed, a spring for restoring said wiper to normal when released, a stepped member moved with the finger hold plate for pushing the wiper forwards, a second spring for restoring said finger hold plate to normal when released, a step formed on said stepped member, a third spring tending to move said stepped member transversely, a driving member attached to the wiper which is pushed forwards by the stepped member and in the normal position engages over

the step to prevent the third spring from moving the stepped member transversely, and switch contacts which are closed by said stepped member when the finger hold plate is in its normal position, said switch contacts moving the stepped member transversely against the action of the third spring. 5

19. A manually operable selector comprising at least two groups of contacts, at least one wiper cooperating simultaneously with said two groups of contacts, and mounted on a wiper carrier, a manually operable member to move said wiper carrier, means for holding the wiper carrier in the position to which it is moved on both groups of contacts, and switching means for selectively transmitting a calling signal through any one of the groups of contacts. 10 15

EDWARD SHIPTON.
